UNITED STATES PATENT OFFICE.

MARTIN WIESER, OF ARMSTRONG, KANSAS.

CISTERNS-PUMP.

SPECIFICATION forming part of Letters Patent No. 225,193, dated March 2, 1880.

Application filed December 18, 1879.

To all whom it may concern:

Be it known that I, MARTIN WIESER, of Armstrong, in the county of Wyandotte, and in the State of Kansas, have invented certain new and useful Improvements in Cistern-Pumps; and I do hereby declare that the following is a full, clear, and exact description thereof, reference being had to the accompanying drawings, and to the letters of reference marked thereon, making a part of this specification.

The nature of my invention consists in the construction and arrangement of a pump to be used for pumping water either from a cistern or a well when the cistern is built at the top of the well, as will be hereinafter more fully set forth.

In the annexed drawings, Figure 1 is a vertical section of my invention. Fig. 2 is a vertical section of a part thereof. Fig. 3 is a detailed view of the top of the well.

A represents a cistern, which is built at the top of the well—that is to say, the upper end of the well terminates in the bottom of the cistern. B represents the well-tube in the well. On the upper end of the well-tube B is a head-piece, C, in which is a downwardly-closing valve, a. This valve can only open upward a certain distance, such distance being limited by means of cross-bars b b. Surrounding the head C is a collar, D, extending above the head a suitable distance and provided on one side with a faucet-barrel, E, which lies horizontal on or close to the bottom of the cistern. In this barrel, near the inner circumference of the collar D, is a check-valve, d, as shown. There is also in the barrel E an ordinary faucet-plug, e, provided with a stem, F, which has a square hole in its upper end. To the collar D is secured a tube or cylinder, G, which extends upward and connects with a spider, H, in the upper portion of the cistern, and prevents the water from the cistern getting into the well. I is the pump-cylinder, attached to the lower end of the pump-stock J, and the lower end of said cylinder is screwed into the collar D. h is the ordinary plunger, connected by a rod, i, with the pump-

handle K above the cover L of the cistern. On the spider H is a swiveled post, m, in which is pivoted a short lever, n. One end of this lever connects with a collar, p, placed between two stationary collars, s s, on a rod, M, which is inserted in the upper end of the faucet-stem F. To the other end of the lever n is connected a rod, t, which passes downward into and through the lower end of the pump-cylinder I, and is immediately above the valve a. At the point where the rod t goes into the pump-cylinder is a packing-box, w, as shown.

By turning the rod M so as to open the faucet E e, and at the same time raising said rod, the rod t will bear down upon the valve a and keep the same closed, so that when the pump is operated the water will be drawn from the cistern. By reversing this—that is to say, turning the rod M so as to close the faucet and then pushing said rod down—the rod t will be raised to release the valve a, and when the pump is operated the water will be drawn from the well.

Having thus fully described my invention, what I claim as new, and desire to secure by Letters Patent, is—

1. The combination, with a pump arranged over a well, of a cistern surrounding the same, and connections leading from both the well and cistern to the pump, substantially as herein set forth.

2. The combination, with the well-tube B and cistern A, of the head C, with valve a, collar D, faucet E e, and the pump, substantially as and for the purposes herein set forth.

3. The combination of the faucet-stem F, rod or handle M, with stationary collars s s, loose collar p, lever n, rod t, and valve a, substantially as and for the purposes herein set forth.

In testimony that I claim the foregoing I have hereunto set my hand this 28th day of November, 1879.

MARTIN WIESER.
